[57] CLAIM

The ornamental design for an electrophotographic copying machine, as shown and described.

DESCRIPTION

FIG. 1 is a front elevational view of an electrophotographic copying machine showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a top and left front perspective view thereof;

FIG. 8 is a top and left front perspective view thereof with the paper feeding and receiving trays in place. In FIGS. 1-7, the paper feeding and receiving trays have been omitted for ease of illustration and clarity.
